UNITED STATES PATENT OFFICE.

OTTO STEINLE, OF QUEDLINBURG, GERMANY.

GOVERNOR.

SPECIFICATION forming part of Letters Patent No. 631,340, dated August 22, 1899.

Application filed May 27, 1899. Serial No. 718,556. (No model.)

To all whom it may concern:

Be it known that I, OTTO STEINLE, a subject of the King of Prussia, German Emperor, and a resident of Quedlinburg, in the Province of Saxony, German Empire, have invented certain new and useful Improvements in and Connected to Governors, (for which a patent application has been filed in Germany on the 29th of April, 1899,) of which the following is an exact specification.

Hitherto the governors offered the serious drawback that when the number of the shaft revolutions was altered suddenly the centrifugal weights produced a great amount of friction and the whole mechanism was used rapidly.

The object of the present invention is to obviate this drawback in regulating automatically the centrifugal weights and is attained by transmitting the alterations of the revolutions of the governor-spindle to the centrifugal weights. Thereby is attained, that the inertia forces and the centrifugal forces are employed for altering the position of the slide.

In order to render my invention more clear, I beg to refer to the accompanying drawings, in which similar letters denote similar parts, and in which—

30 Figure 1 illustrates a detail view of the double lever effecting the transmission of the revolutions to the centrifugal weights. Fig. 2 illustrates a vertical section through the governor. Fig. 3 is a top view of the same.

35 The double lever *a* is rigidly connected to the governor-spindle and by means of levers *d* to the centrifugal weights. Centrifugal weights *g*, acting against springs, slide upon guide-rods *f*, screwed into the slide *b*, rotating loosely around the governor-spindle.

The governor-weights by means of levers *h* are connected to a sliding socket *i*, which in any suitable manner is connected to the steam-valve of the engine. When the revolution of the spindle lessens suddenly, the slide *b*, and consequently the centrifugal weights *g*, will keep up the original rapidity; but the double lever *a*, owing to its rigid connection with the spindle, tends to approach the slide *b*. Thereby the centrifugal weights *g* diverge farther, 45 and consequently the number of revolutions lessens.

The alteration of position of the centrifugal weights is transmitted by means of levers *h* to a sliding socket *i*, from where it is transmitted further to the steam-valve of the engine in any suitable manner.

Having thus fully described the nature of this invention, what I desire to secure by Letters Patent of the United States is—

50 In an improved shaft-governor the combination with a double lever *a* rigidly connected to the governor-spindle, spring-acted centrifugal weights *g* sliding upon rods, levers *d* connecting the centrifugal weights to the double lever *a*, a slide *b* loosely mounted upon the spindle, rods *f* fixed to the slide and carrying the centrifugal weights, levers *h* transmitting the alteration in position of the centrifugal weights to a sliding socket *i*, for the 55 purpose and substantially as set forth.

60 In witness whereof I have hereunto set my hand in presence of two witnesses.

OTTO STEINLE.
